MARKING MACHINE FOR LAUNDRY ARTICLES

Filed Jan. 12, 1925

Inventor
Leonard S. Smith Jr.

by *Douglas & Wagner Attys*

UNITED STATES PATENT OFFICE.

LEONARD S. SMITH, JR., OF CINCINNATI, OHIO.

MARKING MACHINE FOR LAUNDRY ARTICLES.

Application filed January 12, 1925. Serial No. 1,996.

To all whom it may concern:

Be it known that I, LEONARD S. SMITH, Jr., a citizen of the United States, and a resident of Cincinnati, in the county of 5 Hamilton and State of Ohio, have invented a certain new and useful Marking Machine for Laundry Articles, of which the following is a specification.

My invention relates to, and consists in, 10 certain improvements upon that type of marking machines for laundry articles which is illustrated and described in United States Letters Patent Number 927,487 issued to C. W. Canine, July 13, 1909. In machines of this class there is usually provided a series of type wheels arranged side by side, and so constructed that each type wheel may be independently rotated to move a pre- 15 determined type, upon the face thereof, to a position for printing, and when all of the type wheels have been thus moved, the selected types are arranged in line for printing position, and the same combination of letters or numerals may be repeatedly printed 20 from said type wheels while they are held in such position.

In a machine of this kind it is desirable that, when the type wheels have been moved to position for presenting any given combination of letters or numerals at the printing point, said type wheels be firmly and securely held in accurate alinement, and it is also desirable that this accuracy of alinement may be readily, quickly and easily attained, both in the original assembling of 35 the machine parts and subsequently in the event that any type wheels should fail to properly aline with the other.

The object of my invention is to provide 40 means of simple, durable and inexpensive construction, whereby, during the original assembling of the machine, the type wheel moving and locking means may be readily and quickly adjusted with relation to each 45 independent type wheel, so that the types on all of the type wheels will be in line; and

Further to provide means whereby when 50 thus adjusted they may be firmly held in such adjusted position, and in the event that the adjusting and holding mechanism for any type wheel should for any reason be moved so that the corresponding type wheel would not be in alinement with the others, 55 an adjustment to renew the alinement may

be readily and easily made by unskilled operators.

A further object is to effect certain economies in construction and standardization of parts, whereby a single and uniform size 60 and style of type wheel adjusting and locking lever may be utilized for all of the various type wheels in the machine.

My invention consists in the construction, arrangement and combination of the various 65 parts of the device, whereby the objects contemplated are attained, as hereinafter more fully set forth, pointed out in my claims, and illustrated in the accompanying drawings, in which:

Figure 1 shows a side elevation of a part 70 of a marking machine embodying my invention.

Figure 2 shows a detail front elevation illustrating a series of type wheels and their 75 actuating toothed segments and the adjusting and locking levers applied to the segment.

Figure 3 shows an enlarged, detail, sectional view illustrating a portion of one of 80 the toothed segments, a portion of the notched locking bar and one of the adjusting and locking levers, and an adjustable arm for connecting the locking lever with the toothed segment; and

Figure 4 shows a front elevation of same.

Referring to the accompanying drawings, I have used the reference numeral 10 to indicate the frame upon which the type wheels and type wheel adjusting and locking 90 mechanism is mounted. This frame is preferably mounted for tilting movement upon a stationary shaft 11, and 12 indicates a printing platen in stationary position to be engaged by the type wheels when the frame 95 10 is swung through an arc downwardly and forwardly. This construction is now in general use and is known as the drop head construction of marking machines.

Mounted within the frame 10 is a series 100 of type wheels 13. The periphery of each is toothed, and on the outer face of each there is usually placed a type character not shown. These type wheels are independently rotatable on their support. Mounted 105 within the frame 10 is a series of toothed sectors 14, one for each type wheel. They are all pivoted on the shaft 15, and the teeth of each coacts with the teeth of the corresponding type wheel 13, so that a seg- 110

mental movement of the toothed sector through, say for instance, an arc of the length of ten of the sector teeth will effect a corresponding movement of the associated type wheel through an arc of ten teeth space of the type wheel. This construction is of the ordinary kind now in common use and will be readily understood.

Above each toothed sector there is fixed to 10 the frame a notched locking bar 16 designed to aid in holding the toothed sectors in any position to which they may be adjusted.

Above each of the notched locking bars is 15 a locking lever device comprising a body portion 17, to which there is connected an upwardly extended stationary handle 18. Pivoted to the body portion 17 is a lever 19, which lever is in turn pivotally connected to a slide bolt 20 mounted for longitudinal 20 movement in the body 17. Its lower end is preferably beveled to a sharp point at 21, and a spring 22 is provided for yieldingly holding the slide bolt downwardly and the lever 19 at its limit away from the handle 17.

25 My present invention is particularly concerned with the means for connecting these locking lever devices with the toothed sectors, and this means comprises a short arm 23 extended upwardly from the upper end 20 of each sector and formed with two screw threaded openings in vertical alinement with each other to receive the screws 24 and 25. The body 17 is formed with a vertical slot, as shown in Figure 4, and also with two 35 screw threaded openings designed to receive the screws 26 and 27 passing through the slot 28.

Between the short arm 23 and the locking lever device, I have provided an adjustable connecting arm 29, preferably formed of a piece of strap metal and having at its lower end a transverse slot 30 to receive the screw 25, a round opening 31 to fit the screw 24, a transverse slot 32 to receive the screw 27, 45 and a round opening 33 to fit the screw 26.

Upon referring to Figure 2, it will be seen 50 that the body portions of the group of toothed sectors 14 are assembled together side by side in a much smaller space than are the corresponding locking levers. Hence, in order to connect, for instance, the locking lever at the right, as shown in Figure 2, with the corresponding toothed sector 14 at the right, as shown in Figure 2, it is necessary that the 55 arms 23 and 29 extend laterally and then upwardly, and that this lateral inclination in the different arms 29 is at different angles for each toothed sector. Since, however, the arms 23 and also the arms 28 are made of flat metal, they may be readily and easily given the desired shape, and may be cut to the desired length.

In this connection it is to be understood 60 that all of the arms 23 can be made of exactly the same length, and all of the locking

lever devices can be made of identical size and shape, and that it is only necessary to make the arms 29 of slightly different lengths for their different positions in the assembled machine.

Assuming that a machine of this character is being assembled, the operator connects all of the parts as shown, but does not tighten the two screws 27 and 25. He then moves all of the type wheels to position where their types perfectly aline, and when this is being done, all of the locking lever devices stand in position with the beveled lower ends of their locking bolts accurately positioned in one of the beveled notches of the notched locking bar 16. Then the locking lever devices may, if necessary, be tilted forwardly or rearwardly until the bolts 20 project accurately in a direction radially outwardly from the notched locking bars, and in making this adjustment it may at times be necessary to tilt or incline the arm 29 relative to the arm 23, although in most instances it is only necessary to tilt or incline the locking lever device slightly relative to the arm 29, but either or both adjustments may be readily and quickly made, because during such adjustment the type wheels are held in line and the locking lever devices are held in their respective notches. Hence, the operator may readily and quickly make the necessary tilting movements of the arm 29, or the locking lever devices, as the case may be, and then when the bolt 20 is at the proper angle with relation to the notched locking bar, the screws 27 and 25 may then be tightened and the screws 26 and 24 may also be tightened, thus permanently securing together the associated parts, and thereafter when any locking lever device is adjusted relative to its notched locking bar, the corresponding type will be moved to perfect printing position and securely held.

Furthermore, if, for any cause during the use of the marking machine, any type wheel should fail to properly aline with the other, an unskilled operator may readily and quickly effect a perfect alinement by loosening the screws 24, 25, 26 and 27, or some of them, and moving the parts to position for alining the type and keeping the locking bolts 20 in radial positions relative to the notched locking bar, and then again tighten the said screws.

I claim as my invention:

1. In a machine of the class described, the combination of a toothed type wheel, a toothed sector co-operating with the type wheel, a notched locking bar adjacent to the toothed sector, a lever locking device including a slide bolt to co-operate with and enter the notches of the notched locking bar, and a means for adjustably connecting the said sector and the lever locking device, comprising an arm adjustably secured

to the toothed sector and also adjustably secured to the lever locking device.

2. In a machine of the class described, the combination of a toothed type wheel, a toothed sector co-operating with the type wheel, a notched locking bar adjacent to the toothed sector, a lever locking device including a slide bolt to co-operate with and enter the notches of the notched locking bar, and a means for adjustably connecting the said sector and the lever locking device, comprising an arm having at its lower end a transverse slot and a round opening above it, and having at its upper end a transverse slot and a round opening above it, screws passed through said opening and slot in the lower end of the arm and seated in the sector, and screws passed through the opening and slot in the upper end of the arm and seated in the lever locking device.

3. In a machine of the class described, the combination of a toothed type wheel, a toothed sector co-operating with the type wheel, a notched locking bar adjacent to the toothed sector, a lever locking device including a slide bolt to co-operate with and enter the notches of the notched locking bar, and a means for adjustably connecting the said sector and the lever locking device, comprising an arm fixed to the sector and provided at its upper end with a transverse slot and a round opening above the slot, and screws passed through the said slot and arm and seated in the said lever locking device, for the purposes stated.

4. In a machine of the class described, the combination of a series of toothed type wheels rotatively mounted side by side, a series of toothed sectors mounted for co-operative movement with the type wheels, each sector being formed with a short arm extended upwardly from it, a series of notched locking bars one for each toothed sector, said notched locking bars being spaced apart from each other at greater distances than are the corresponding toothed sectors, a series of lever locking devices, one for each notched locking bar and all of the same size and shape, and each having a slide bolt to engage the notches of its corresponding notched locking bar, each also having a slotted lower end provided with two screw threaded openings, and an adjustable connecting arm for each of said lever locking devices, said arms being of different lengths and each being formed at its lower end with a transverse slot and a round opening, and also at its upper end with a transverse slot and a round opening, the upper end being inserted in the slot in the corresponding locking lever device, screws passed through said opening and slot in the lower end of the arm and seated in the adjacent toothed sector, and screws passed through the lever locking device and through the slot and opening in the upper end of the arm, substantially as and for the purpose stated.

Des Moines, Iowa, December 18, 1924.

LEONARD S. SMITH, JR.
